BOOK END

Filed Jan. 11, 1932

Inventor
Vernon M. Spurr

By
David Petty Moore

Attorney

UNITED STATES PATENT OFFICE

VERNON M. SPURR, OF BROADALBIN, NEW YORK

BOOK-END

Application filed January 11, 1932. Serial No. 586,059.

The present invention relates to improvements in book ends, one object of the invention being the provision of a sheet metal book end, which is so constructed that when in use to support is itself supported by the books and has means to prevent the cover of the outer book from spreading or opening up, and while so acting to be entirely invisible.

10 Another object of this invention is the provision of a sheet metal book end, which is simple, inexpensive and durable in construction and to be constructed and is thoroughly efficient and practical in use.

15 While I have illustrated one form of the invention in the accompanying drawing, it is evident that the same may be modified to certain degrees and still be within the scope of the invention.

20 In the accompanying drawing:—

Figure 1 is a perspective view of two ends in use, the ends being shown in dotted lines.

Figure 2 is a plan view of a blank from which the end is made, dotted lines showing 25 the bending line while the tab is in full lines.

Figure 3 is a perspective view of a modified form of book end.

Referring to the drawing, and more particularly to Figures 1 and 2, the numeral 5 designates the blank of sheet metal. This is so shaped and sized, that when bent on line 6, as to forming the two leaves 7 and 8, disposed at right angles to each other.

30 A lip or tab 9 is cut from the leaf 8 at the junction with the leaf 7 and is bent outwardly and upwardly to form a hook exteriorly of the book end, and the underside of the base leaf 7 is covered with a sheet 10 of felt or other soft material, to prevent marring furniture when in use as illustrated in Figure 1.

It will be noted that the width of the leaves 7 and 8 are slightly less than that of the books B, and that the upper edge 11 of the leaf 8 terminates within the upper edges of the book, so that when the ends are in book racking position, the only portion visible is the tab or hook 9, which with the leaf

50 8 receives the lower edge of the cover of the

outer book and thus prevents the cover from spreading or opening, as would be the case if this hook were not provided. Also the leaf 7 is disposed below the first and several of the adjacent books, while the leaf 8 is 55 disposed between the outer cover leaf and the fly leaf of the outermost book.

As the end can be made of sheet metal, such as steel, aluminum, and the like, a very light and yet strong end can be produced.

60 Where it is desirable to ornament the book end, the leaf 8' as viewed in Figure 3, may be provided with the integral or separate bent over ornamental flap 12, which when the books are being racked thereby is 65 visible exteriorly of the upper edge and outer face of the cover of the end book.

From the foregoing description taken in connection with the drawing, it is evident that a very practical invisible book end is 70 here provided, and one that is quickly and easily put into or removed from use, and that being exceedingly light in weight and being held in place by the books that it itself racks, will not mar or scratch the furniture 75 or floors should it be dropped. Also that by making them practically counter parts, a great number for shipment may be nested one within the other.

What is claimed, is:—

80 1. A book end, comprising a piece of sheet metal bent transversely to provide two leaves at right angles to each other, and means at the junction of the angle for holding the cover against spreading or opening out when 85 one of the leaves is below the first and adjoining of the racked books and the remaining leaf is between the outer cover and adjacent page of the first book of the rack.

90 2. A book end, including a piece of sheet metal bent transversely to provide two leaves at right angles to each other, and means at the junction of the angle for holding the cover of the book against spreading or opening out, said means being a hook forming 95 with the adjacent portion of the sheet a receptacle for the lower edge of the cover of the book.

3. A book end including a piece of sheet metal bent transversely to provide two 100

leaves at right angles to each other, and means at the junction of the angle for holding the cover of the book against spreading or opening out, there being formed at the 5 upper edge of one leaf a bent over ornamental flap.

4. A book end, comprising a strip of sheet metal bent substantially L-shaped in side elevation and having a hook excised from 10 one terminal thereof adjacent the angle so as to provide a cover receiving member when the respective terminals of the end are resting below the end book and between the outside cover and the adjacent page thereof.

15 In testimony whereof, I affix my signature.
VERNON M. SPURR.
